LIQUID DISPENSING DEVICE

Arthur N. Severson, Milwaukee, Wis.

Application March 24, 1937, Serial No. 132,777

5 Claims. (Cl. 215—4)

This invention appertains to liquid dispensing devices, and more particularly to means for forcing liquids under pressure from a bottle when needed, such as from laboratory wash flasks.

5 In laboratory work the liquid is generally forced from the flask by blowing into the same through a mouth-piece or tube, and when sufficient pressure is reached the liquid is expelled through a delivery nozzle. Many difficulties are 10 inherent with a flask of this type. The mouth-piece is unsanitary and is liable to collect poisons from the laboratory, and the flask cannot be conveniently used in confined spaces.

It is, therefore, one of the salient objects of 15 my invention to provide means for manually creating and holding a pressure in the flask, which will not only permit the expeditious delivery of the liquid, but which will not interfere with the free manipulation of the flask itself.

20 Another important object of my invention is the provision of a flask or bottle having an elongated neck with a compressible bulb fitted around the neck, having means permitting the intake of air and the expelling of air into the 25 flask, the neck of the flask carrying a sealing stopper and a delivery tube extending to the bottom of the flask, with an outlet nozzle arranged exteriorly of the flask.

A further important object of my invention 30 is the provision of means associated with the stopper for permitting the bleeding of air from the flask when it is desired to stop the delivery of the liquid from the flask.

A still further object of my invention is to 35 provide a laboratory wash flask of the above character, which will be durable and efficient in use, one that will be simple and easy to manufacture, and one which can be placed upon the market at a reasonable cost.

40 With these and other objects in view, the invention consists in the novel construction, arrangement, and formation of parts, as will be hereinafter more specifically described, claimed, and illustrated in the accompanying drawing, in 45 which drawing:

The figure is a central longitudinal section through a laboratory flask embodying the principles of my invention.

Referring to the drawing in detail, the numerals 50 at 10 indicate a bottle or flask having the body portion thereof provided with an elongated neck 10'. The neck is normally closed and sealed by a rubber stopper 7, and this stopper has fitted therein a relief tube 1. Formed on the relief tube 55 1 are radially extending knobs 2, which are fitted

in the elastic stopper. This construction allows the turning of the relief tube by hand, for a purpose which will be later set forth, and to insure the automatic returning of the tube to its normal position when the tube is released.

5 The stopper 7 also carries a glass tube 3, which extends through the neck and into the body portion of the bottle or flask. As illustrated, the tube terminates in close relation to the bottom wall of the flask and is bent at an angle so that 10 when the flask is tipped in one direction the lower end of the tube will still be immersed in any liquid left in the bottle. The upper end of the tube 3 is bent downwardly at an angle, as at 15 3', and is connected by a piece of flexible tubing 4 with a glass outlet nozzle 5. The outer end of the nozzle 5 is tapered, as at 6, so that liquid dispensed from the nozzle will be in the form of a fine spray.

Around the neck 10' is placed a compressible 20 bulb 8, and this bulb is preferably provided with an inner sleeve 8', which closely embraces the neck of the bottle. The sleeve 8' is connected with the opposite ends of the bulb, and thus an air chamber is formed around the sleeve 8'. The bulb is provided with an air inlet valve 9 and an air outlet valve 11. These valves can be of any preferred character, and it is to be noted that the valve 11 is in the nature of a rubber nipple, which extends through an opening in the 30 neck 10', so that when the bulb is compressed air will be forced into the bottle.

In use of my flask the bulb 8 is compressed by the hand, and the air contained in the bulb will be forced into the flask. Upon release of the 35 bulb air will be taken into the bulb through the valve 9, and consequently when pressure is again placed on the bulb additional air will be forced into the flask. When a sufficient pressure is reached, the liquid will be forced out of the flask 40 through the tube 3 and the nozzle 5.

To permit the quick release of pressure from the flask when it is desired to stop the flow of liquid through the nozzle, the tube 1 can be brought into play. This tube 1, at a point intermediate its ends, is provided with an air inlet port 12, and this port is adapted to be brought into communication with a longitudinally extending channel 13 formed in the stopper 7. This channel 13 communicates with the interior of the 50 bottle or flask. Normally, the opening 12 is at one side of the channel 13, and when it is desired to relieve pressure the tube is rotated so as to bring the opening 12 into communication with the channel. Upon release of the tube the same 55

will be brought back to its normal cut-off position by the inherent resiliency of the stopper 7 acting upon the knobs 2.

While I have shown my invention applied to

- 5 a flask or bottle, it is to be understood that the same can be incorporated with various types of receptacles.

Changes in details may be made without departing from the spirit or the scope of my invention, but what I claim as new is:

1. A device for dispensing liquids comprising, a receptacle having an elongated neck, a stopper sealing the neck, a delivery tube extending through and carried by the stopper, said tube 15 terminating adjacent to the lower end of the receptacle, and a bulb closely embracing the elongated neck and having communication therewith for forcing of air under pressure into the receptacle.
2. A device for dispensing liquids comprising, a receptacle having an elongated neck, a stopper normally sealing the neck, a dispensing tube carried by and extending through the stopper into the receptacle, an outlet nozzle carried by the tube, a resilient bulb closely embracing the elongated neck having an air inlet valve communicating with the atmosphere, and an air outlet valve communicating with the receptacle.
3. A device for dispensing liquids comprising, 30 a receptacle having an elongated neck, a stopper normally sealing the neck, a dispensing tube carried by and extending through the stopper into the receptacle, an outlet nozzle carried by the tube, a resilient bulb closely embracing the elongated neck having an air inlet valve communicating with the atmosphere, an air outlet valve com-

municating with the receptacle, and means for quickly releasing pressure in the receptacle.

4. A laboratory wash flask comprising, a body, an elongated neck on said body having an opening therein, a stopper sealing the neck, a delivery tube carried by and extending through the stopper into the body, an outlet nozzle carried by the outer end of the tube, a resilient bulb surrounding the neck having an inner sleeve closely embracing the neck and connected with the opposite ends of the bulb, said bulb having an air inlet valve communicating with the atmosphere, an air outlet valve on the bulb communicating with the opening in the neck.

5. A laboratory wash flask comprising, a body, 15 an elongated neck on said body having an opening therein, a stopper sealing the neck, a delivery tube carried by and extending through the stopper into the body, an outlet nozzle carried by the outer end of the tube, a resilient bulb surrounding the neck having an inner sleeve closely embracing the neck and connected with the opposite ends of the bulb, said bulb having an air inlet valve communicating with the atmosphere, an air outlet valve on the bulb communicating 20 with the opening in the neck, said stopper having a way communicating with the neck, a tube having a closed inner end carried by the stopper, means anchoring the last named tube to the stopper, said last named tube having an air inlet 25 opening normally disposed out of communication with the channel, said opening being adapted to be brought into communication with the channel upon turning movement of said last named tube.

ARTHUR N. SEVERSON.
